COUNTING DEVICE

Marcel Antoine Demeulenaere and Robert Demeulenaere,
New York, N. Y.

Application April 8, 1953; Serial No. 347,578

13 Claims. (Cl. 235—136)

This invention pertains to accumulator mechanisms or counting devices, comprising a series of digital drums of ascending indicia order together with interlinking mechanisms for appropriately actuating the same.

Heretofore accumulators or counters of the general type aforesaid have comprised both continuous and discontinuous types. In the continuous types all indicating drums advance simultaneously, but not equally. In counters of this type based on the decimal system, the successive drums advance proportionally to one-tenth, one-hundredth, one-thousandth, etc. of the first drum. Such counters are difficult to read, by virtue of their continuous motion, but the driving effort is very evenly distributed between successive drums.

The discontinuous types of counters presently in use have a Geneva transmission between the counter drums, each drum advancing by one unit for each complete revolution of the preceding drum. In counters of this type when the setting is at 999999, for example, and one unit is added at great speed, severe strains are imparted to the transmission teeth and shaft. Conversely, when one is added to 999999 at a very low speed, the backlash between gears gives a poor alinement of the digits.

By reason of limited space requirements, the carry-over gear which bridges two contiguous counter drums, usually has only eight teeth, whereas the counter drums have forty teeth. When the counter drums are required to be extremely small, the carry-over gears and their supporting shaft become quite small and fragile. This remains the case even though instead of an 8/40 ratio of gear teeth, a ratio of 6/20 is employed.

Also the resetting of such counters presents serious technical difficulties. The Geneva type of carry-over gear, prevents simultaneous rotation of the counter drums for resetting. Either the carry-over gears have to be disengaged, which makes re-engagement quite difficult, or the counter drums have to be made independent of these gears, through positioning pawls. Although the latter solution has proved most popular, it limits the speed of operation, because the inertia of the drums must be overcome by the tension of the positioning pawl springs.

The counting devices of the present invention eliminate the disadvantages of the prior art counters above referred to, and embody the advantages of both continuous and discontinuous counters, while eliminating their disadvantageous features.

In some counters of the present invention when one is added at great speed to 999999, the effort is no greater than at any other status of operation of the counter. Also when one is added at low speed to 999999 with counters of the present invention, the alinement of the digits remains precise at all times, all backlash being taken up. Instead of the necessity for employing gear ratios of 8/40 or 6/20 between the carry-over gears and the counter drums, as in prior constructions, the present invention permits gear ratios of 6/10; still much less space is taken up by the carry-over gears than by prior devices. In fact, in certain modifications of the present invention as described below, but two teeth on the carry-over gear are required, and these are disposed between and substantially within the peripheries of adjacent counter drums, thereby minimizing space requirements.

With the counters of the present invention, resetting is easily accomplished with certain modifications, since the counting drums may be turned in reverse, and all together. In certain modifications no inertia problems are

involved, as the functioning does not depend on springs nor require springs and as special precautions have been taken. In other modifications employing springs, they operate in such manner that energy is stored in the spring during nine-tenths of a revolution of a lower indicia counter drum, which energy is automatically released during the remaining one-tenth of a revolution to actuate the next higher indicia drum.

Reference will now be had to the accompanying drawings for detailed explanation of the various modifications of counting devices in accordance with this invention.

In the drawings:

Fig. 1 is a side elevation partly in axial section as taken at 1—1 of Fig. 2, while Fig. 2 is an end elevation taken at 2—2 of Fig. 1, of a counting device in accordance with one modification of the invention.

Fig. 3 is a side elevation, partially in axial section as taken at 3—3 of Fig. 4, and Fig. 4 is an end elevation as taken at 4—4 of Fig. 3 of a second modification of the invention.

Fig. 5 is a perspective view of one form of carry-over element employed in the device of Figs. 3 and 4;

Fig. 6 is a top plan view of such a carry-over element;

Fig. 7 is an axial sectional elevation as taken at 7—7 of Fig. 8, and Fig. 8 is an end elevation as taken at 8—8 of Fig. 7, of still a further modification of the invention, while Fig. 10 is an end elevation as taken at 10—10 of Fig. 9.

Fig. 9 is a side elevation of a counter and disengagable clutch mechanism in accordance with the invention for connecting the counter to a driving mechanism, Fig. 11 being a transverse sectional elevation thereof as taken at 11—11 of Fig. 12, while Fig. 12 is an end elevation as taken at 12—12 of Fig. 11.

Fig. 13 is a sectional view of the apparatus shown in Fig. 11 taken substantially along line 13—13;

Fig. 14 shows the embodiment of the counter mechanism of Figs. 11—13 but modified by the inclusion of a resetting mechanism, together with a clutch arrangement;

Fig. 15 is a sectional view of the device shown in Fig. 14 taken substantially along line 15—15; and

Fig. 16 is also a sectional view of the device shown in Fig. 14 taken substantially along line 16—16.

Referring to Fig. 1, the counter thereof, comprises a drive shaft 1, journaled to a frame 2. Keyed to the drive shaft 1 by means of a pin 3 is a lower indicia drum 4, representing, for example, units of the decimal system, this drum bearing on its peripheral face equally spaced digits, ranging from 0 to 9, as shown for the drum 23 at the left. The drum 4 has integral therewith a hub 5, which is eccentric to the shaft. Journaled to the eccentric hub 5, and hence rotatable thereon, is a plate or disc 6, having upstanding from its left hand surface as viewed in Fig. 1, a series of nine equally spaced pins, as at 7, disc 6 being hereinafter referred to as a "spur gear".

Journaled to and hence rotatably mounted on the drive shaft 1, adjacent the drum 4, is a second and higher indicia drum 8, similar to drum 4, having cut or formed in its right hand face, as viewed in Fig. 1, an internal ring gear 9, provided with ten equally spaced, substantially semicircular notches or cutouts, as at 10, adapted to mesh progressively with the pins 7 of the spur gear 6, as the drive shaft is rotated, as described hereinafter.

Mounted in the lower portion of the frame 2, is a shaft 11, which parallels the drive shaft 1, and to which is journaled an angle shaped pawl 12, one leg 13 of which normally engages a lug 14 projecting from the outer periphery of the spur gear 6. The other leg 15 of pawl 12 has projecting from the left hand face thereof, as viewed in Fig. 1, a pin 16, which normally seats in a notch, such as 17, of a ratchet face 18, formed in the outer right hand periphery of drum 8, as viewed in Fig. 1. Angularly spaced from the projecting lug formed on plate 6, is a second lug 19 having projecting therefrom a pin 20 to which one end of a tension spring 21 is secured, the opposite end of this spring being connected to a pin 22 projecting from the leg 15 of pawl 12.

If desired, a third or any requisite additional number

of still higher indicia drums, such as 23, each similar to drums 4 and 8, may be journaled to the drive shaft 1, in the same manner as drum 8, and interconnected with each other in the manner above described with reference to drums 4 and 8.

In the operation of this device, as drive shaft 1 is rotatably driven in a clockwise direction, as viewed in Fig. 2, it will carry with it the first drum 4 keyed thereto, thus causing the pins 7 of the spur gear, rotatable on the first drum eccentric 5, successively to engage notches 10, of the internal ring gear 9 formed on the next drum 8. Thus starting from the position shown in Fig. 2 with pin 7a seated in notch 10a, the meshing will progress in the direction of pins 7b, 7c, etc., seating successively in the notches 10b, 10c, etc., thus progressively to rotate the spur gear 6, in a counterclockwise direction, until the drive shaft 1 has completed nine-tenths of a complete revolution, in which position the pin 7a will be in the position 7a' for seating in the notch 10 of the internal ring gear 9. This counterclockwise displacement of plate 6 as the drive shaft is rotatably driven clockwise, results from the fact that the second drum 8, is locked against rotative movement by the seating of the pin 16 of pawl 12 in a notch 17 of the ratchet face 18 of drum 8. As the spur gear 6 is thus rotatably displaced counterclockwise, the projecting lug 14 thereof will ultimately engage the pin 16 of pawl 12, at the instant that pin 7a of plate 6 seats in the notch 10 of the internal ring gear 9. Also as the spur gear 6 is thus displaced, the spring 21 extending between lug 19 of plate 6 and arm 16 of pawl 12, is increasingly tensioned, so that when lug 14 of plate 6 engages pin 16 of the pawl, and thus disengages this pin from the ratchet face 18, drum 8 will be rotated one-tenth of a turn by the restoring action of spring 21, which now rotates plate 6 clockwise, as pin 16 slides along the adjacent face 18a of the ratchet, and ultimately seats in the succeeding notch 17a thereof to arrest the further movement of drum 8. It should be borne in mind in this connection that since pin 7a is now seated in notch 10 of drum 8, the clockwise rotative movement imparted to the spur gear 6 by the restoring action of spring 21, is thus transmitted to the drum 8, thereby correspondingly rotating the latter $\frac{1}{10}$ of a turn.

This sequence of operations is continued for each complete cycle of rotation of the drive shaft 1, carrying with it the lowest indicia drum 4, until the second drum 8 has been stepped around to successive extents of one-tenth turn each, until drum 8 has completed a cycle of rotation, at which time pawl 24 of the drum will be actuated in a manner similar to that above described with reference to pawl 12, whereby drum 8 now rotates the next higher indicia drum 23, one-tenth of a turn or one digit thereon.

Thus in the embodiment of the invention above described, since there are nine pins such as 7, in each spur gear 6 of a lower indicia drum, and since there are ten notches such as 10 in the internal ring gear such as 9, of each next higher indicia drum, such as 8, the spur gear 6 will creep in anticlockwise rotation by one-tenth of a turn, during nine-tenths of the turn of clockwise rotation of the drum on which such spur gear is mounted. But since the spur gear 6 is under tension of the spring 21, and the lug 14 of this gear will have traveled by one-tenth of a turn anticlockwise to displace the pin 16 of the pawl from the ratchet face 18, the spring will thereby be free to pull the spur gear 6 and with it the second drum with which that plate meshes, back to the position shown in Fig. 2 of the drawing, by clockwise rotation, thus to rotate the next higher indicia drum one-tenth of a turn or one digit, in the clockwise direction. That is to say, each complete revolution of the shaft 1, and consequently the first drum 4, will produce one-tenth of a turn of the next adjacent drum 8. And each complete turn of the second drum 8 will produce one-tenth of a turn of the next higher drum such as 23, and so on irrespective of the number of digital drums mounted on shaft 1.

It is further to be noted with this modification that the counterclockwise angular shifting of each spur gear, such as 6, occurs during nine-tenths of a complete revolution of the preceding drum, during which energy is stored in the spring 21, which is employed on the carry-over of the next higher indicia drum, following the last one-tenth turn of the preceding drum.

Another feature to be observed with respect to this

construction is that the backward creep of the spur gear 6, which is obtained in counting devices heretofore known, by means of compensating cams and even more complicated constructions, is secured in the above modification, by the simple expedient of retaining the next higher indicia drum, by means of the pawls such as 12, against rotation during nine-tenths of a turn of the next lower indicia drum.

In the next modification of the invention to be discussed, namely, that illustrated in Figs. 3 and 4, each higher indicia drum is retained immobile during nine-tenths of a revolution of the next lower indicia drum, by means of a Geneva cam.

Referring now to the Figs. 3 and 4, this modification of the invention comprises a high speed counter, which can be extended to include a large number of indicia drums, for counting up to any desired magnitude, because it embodies a backlash compensating mechanism.

In this modification the drive shaft 31, is again journaled in a frame 32. Keyed to shaft 31, are a driving gear 33, and the lowermost indicia drum 34. Drum 34 has integral therewith an eccentric hub 35, to the outer end of which is journaled a spur gear 36, which is thus rotatively free on the eccentric. This gear is provided on its outer face with a series of nine equi-spaced teeth, as at 37.

The next adjacent higher indicia drum 38, is generally similar to drum 34, except for being journaled to and hence freely rotatable on the drive shaft 31. Drum 38 has hollowed out of its face 39, opposed to drum 34, an internal ring gear 40, consisting of ten equi-spaced teeth, such as 41, alternating with notches or depressions, as at 42. The spur gear 36 is mounted in meshing relation with the ring gear 40, in the manner shown most clearly by the dotted contour lines 37, 41, 42 of Fig. 4.

As in Fig. 4, gear 36 has formed in its peripheral edge, a pair of similarly shaped depressions or notches, 43, 44, which are angularly spaced, to provide therebetween, a prong or tooth 45. Mounted on the first driven hub 35, adjacent gear 36, is a second plate 46 shaped to form a prong 47 similar to prong 45 of gear 36, this plate having the configuration in plan shown by the contour lines 48 of Figs. 4 and 8, and the prong 47 thereof being superimposed in the former showing on the prong 45 of gear 36, these prongs being mounted in contiguous but sliding surface engagement, as shown in Fig. 3. Also mounted on the first driven hub 35, is a cam 49, having the contour shown in full lines in Fig. 4. The prong 47 and cam 49 are keyed to the hub 35, as at 50, and hence rotatable therewith.

Mounted in the lower portion of the frame 32, is a shaft 51 which parallels the drive shaft 31. Journaled to shaft 51, is a carry-over member 52, which partakes of an oscillatory movement as explained below, and which has integral therewith a pair of spaced prongs 53, 54, positioned respectively to enter the notches 43, 44, of gear 36, with the prong 45 thereof disposed between the prongs 53, 54 of the carry-over.

Formed on the backside (Figs. 4 and 5) of the carry-over 52, is a Geneva cam 55, having an arcuate cam face, as at 56, adapted to engage complementary arcuate, Geneva cutouts, such as 57, formed in the peripheral edge of the next higher indicia drum 38. These cutouts are best shown in side elevation at 58 for the still next higher indicia drum 59 of Fig. 3.

In the operation of this device, assume that the various components described are in the relative positions shown in Fig. 4. If now the drive shaft is rotated clockwise, it will rotate therewith, the drum 34, the prong 47, and the cam 49, since all of these components are integral with the drive shaft. As these components are thus rotated clockwise, the spur gear 36 will be rotated slowly counterclockwise, due to progressive engagement of the spur gear teeth 37 with the depressions 42 in the internal ring gear 40 of the next drum 38, inasmuch as this drum 38 is locked against rotation by engagement of the carry-over Geneva cam 55, with one of the Geneva cutouts 57 of drum 38. This counterclockwise rotation of the spur gear 36 will rotate the carry-over 52 clockwise, by engagement of the prong 45 of the spur gear 36 with the prong 54 of the carry-over.

During nine-tenths of one complete revolution of the drive shaft, the spur gear 36 will thus be rotated counterclockwise, by one-tenth of a complete revolution of the drive shaft, and will thereby rotate the carry-over 52

to the extent that prong 54 will assume the dotted line position shown at 54a, while prong 53 will assume the previous position of prong 54. As the drive shaft continues to be rotated through the final one-tenth of its complete cycle, the leading edge of the cam 49 will engage the carry-over prong 54 and further rotate it clockwise (Fig. 4) to position 54b, sufficiently for the arcuate face 56 of the carry-over Geneva cam 55 to swing clear of the tooth 57', separating the Geneva cutouts 57 of drum 38, in which the cam 55 has been engaged, thus freeing drum 38 for rotation. Thereupon, while so freed, and as the clockwise rotation of the drive shaft 31 continues, the prong 47, rotating with the drive shaft and drum 38, will engage the arm 53 of the carry-over, and swing it quickly back, by counterclockwise rotation, to the full line position shown in Fig. 4, thus restoring the carry-over to its initial setting.

As the carry-over is thus swung back, it carries with it the spur gear 36, by a clockwise angular shift of the latter, due to engagement of the carry-over arm 54 with the spur gear prong 45. And since the spur gear 36 is in meshing engagement with the internal ring gear 40 of the drum 38, and since this drum is now free to rotate, drum 38 will be rotated by one-tenth of a turn, but will be prevented from rotating any additional amount due to the fact that the arcuate face 56 of the carry-over Geneva cam 55, is now in engagement with the arcuate face of the next succeeding Geneva cutout 57 of drum 38.

All components of the first counter drum 34 have thus been restored to the relative positions shown in Fig. 4, and the second drum 38 has been rotated one-tenth of a turn or one digit. This same cycle of operations is repeated over and over again for succeeding revolutions of the drive shaft 31, each revolution thereof stepping the second counter drum around one digit, in the manner above described.

By identically the same sequence of operations the second counter drum 38 steps the next counter drum 59 around one-tenth of a turn or one digit, for each succeeding revolution of counter drum 38, and so on for any number of additional counter drums journaled to the drive shaft 31.

The cam 49 serves to prevent locking of the carry-over through backlash. Thus suppose that through backlash, the prong 54 of the carry-over would not, in the absence of cam 49, quite reach the position shown by the dotted line 54b, and thus would be slightly delayed in reaching that position. In that event, the cam 49 will force it into that position, because, as is clearly shown in Fig. 3, the thickness of the carry-over prong 54 extends into the plane of cam 49, whereas this cam is disposed in a plane above that of the carry-over prong 53, and hence clears the same, so that prong 53 of the carry-over is only engaged by prong 45 of the spur gear 36. The carry-over prong 54 also meshes with the other side of spur gear prong 45, and in addition extends into the plane of cam 49, to be actuated thereby as aforesaid.

Operation of the mechanism may be improved by the addition of a tensioning spring 60, stretched between a pin 61 on the carry-over and a fixed support 62, to impart additional impetus thereto during the carry-over.

The counting device of this modification of the invention possesses a very strong carry-over part, instead of the small and delicate part usually encountered in other counting devices, but one which, nevertheless, occupies no more space than the aforesaid delicate parts of said prior devices, because the actuating carry-over mechanism is disposed within the peripheries of the counting drums.

The modification shown in Figs. 9 and 10, comprises a drive shaft 71, journaled in a frame 72. Keyed to the drive shaft is a hub 73, on which is mounted a drum 74 secured to the hub. As shown in Fig. 9, this drum preferably comprises a pair of cup-like, thin, sheet metal stampings, 74a, 74b, fitting one within the other and secured together. At its left extremity, Fig. 9, this drum has formed therein, an eccentric 75, on which is rotatably mounted a flat, spur gear 76, having nine teeth on its outer periphery, as at 77. This spur gear meshes with an internal gear of ten teeth, as at 78, formed in the opposed face of the next drum 79, the latter being journaled to and hence rotatable on shaft 71.

Projecting from the face of the spur gear 76, opposed to that of drum 74, is a pin 80, which is engaged in a

slot 81 of a carry-over part 82. This carry-over part is simply a sheet metal stamping, bent over on its self as shown in Fig. 9, to provide, in different planes, the slot-like opening 81 and a pair of oppositely disposed legs 83a, 83b. The carry-over is pivotally mounted, as at 84, on a shaft 85, the latter being mounted on the frame 72, in the manner shown in Fig. 9. The carry-over 82 is interposed between the first drum 74 and the spur gear 76, with the pin 80 of the latter engaging the slot 81 of the carry-over as above explained.

Projecting from the left face, Fig. 9, of the drum 74, is a pin 86, adapted to engage the legs 83a, 83b, of the carry-over, as explained below.

With the mechanism as thus far described, and assuming the second drum 79 to be held immobile, when the drive shaft 71, and with it the first drum 74, is rotated clockwise, Fig. 10, from the initial position shown, and through nine-tenths of a complete revolution, the spur gear 76 will be rotated counterclockwise by one-tenth of a turn. In so doing, it will swing the carry-over 82 in a clockwise direction, from the position shown in the drawing, to a position wherein leg 83b occupies the position shown for leg 83a, due to engagement of the spur gear pin 80 with the slot 81 of the carry-over. Thereupon the pin 86 of the first drum 74, will, during the final one-tenth of the revolution of this drum, enter between the legs 83a, 83b of the carry-over, and by engaging the inner edge of leg 83b thereof, thus swing the carry-over rapidly back to its initial position, as shown in Fig. 10. In thus being swung back to its initial position, the carry-over will now rotate the spur gear 76 clockwise, and since this spur gear is in meshing engagement with the internal gear of the second drum 79, the second drum will also be rotated through one-tenth of a turn, or in the amount of one digit.

The mechanism for holding the second drum 79 immobile except during the carry-over will now be described. Between the carry-over 82 and the spur gear 76, there is interposed a plate 87, of elongated configuration, as shown in Fig. 10. This plate has formed in its opposite ends, longitudinally extending cutouts or slots, as at 88, and is mounted for longitudinal displacement between the aforesaid shaft 85, carried by frame 72 at the top thereof, and a similar shaft 89, carried by frame 72 at the base thereof. The plate 87 extends between the shafts 85, 89 with the longitudinal cutouts, such as 88, engaging these shafts, respectively. The plate 87 is also provided with a central aperture 90 of the configuration shown in Fig. 10, and through this aperture, the pin 80 of the spur gear 76, extends into the carry-over slot 81.

The left side of drum 74, as viewed in Fig. 9, has formed therein an indented cam track 93, of roughly D-shaped configuration, as shown in Fig. 10. Into this cam track extends a pin 94 mounted on the right face, Fig. 9, of the spur gear 76.

Assuming now that the components of the counter are initially in the relative positions shown in Fig. 10, if the drive shaft 71, and with it the first drum 74, is turned a little less than one-tenth of a turn in the clockwise direction, the pin 86 on drum 74, will travel alongside of the curved inner face of the carry-over leg 83b, thus preventing the carry-over from swinging to the left. The carry-over is already prevented from swinging to the right, because the pin 80, which extends into the cam slot 81, through the plate 87, is stopped against the right hand side of the opening 90 in this plate. Thus, the carry-over 82, and consequently the next drum 79, are locked in position, relative to each other, throughout nearly one-tenth of a turn, of the first drum. As the system is symmetrical, the same is true for the opposite direction of rotation of the first drum 74.

In view of the fact that the carry-over 82 is thus locked in position throughout substantially two-tenths of a revolution of the first drum, it is thus established that the second drum 79 need only be locked in position during a little more than seven-tenths of a turn, being thereupon freed to rotate for the remaining one-tenth of a turn, to permit the carry-over to actuate the same as above stated. To lock the second drum 79 during this remaining seven-tenths of a turn, the plate 87, is driven downwardly, by the action of the cam track 93 in the preceding drum and the pin 94 of the spur gear, engaging this cam track. As the plate 87 is thus driven downwardly, lugs 95, Fig. 9, on the left side and at opposite ends of the plate 87,

engage one of a series of ten notches 96 formed about the periphery of drum 79, whereby the plate 87 locks this drum in position, until the plate is subsequently driven upwardly again by the action of the cam track 93 and the pin 94 coacting therewith.

During this remaining seven-tenths of a turn of the first drum, the spur gear 76, will, of course, be free to rotate on the eccentric 75 of the first drum, and will thus swing the carry-over 82 to the left from the position shown in Fig. 10, until, as above stated, the right leg 83b thereof, occupies the position shown for 83a. Thereupon, and as above stated, the pin 86 of the first drum 74, will, during the final one-tenth of the revolution of this drum, enter between the legs 83a, 83b of the carry-over, and by engaging the leg 83b thereof, will swing the carry-over rapidly back to the position shown in Fig. 10, during which interval the second drum 79 will be unlocked, due to upward displacement of the plate 87, by virtue of co-action between the cam track 93 and the pin 94 engaging the same.

Still referring to Fig. 10, and starting with the position of the components as shown in this figure, it will be observed that during the first one-tenth of a turn of the first drum 74, the spur gear 76 cannot rotate counterclockwise, to any substantial degree, as it should, since during the interval the carry-over is locked in position in the manner above explained. The counterclockwise rotation of the spur gear fortunately starts very slowly, but picks up speed as the first drum continues to rotate and the pin 86 thereon swings clear of the carry-over leg 83b. Thus, for the first one-tenth of a turn, the counterclockwise rotation of the spur gear is very small, but increases progressively in rate of motion for each additional one-tenth turn up to the fifth one-tenth. Thereupon, its rate of rotation decreases in the same proportion at it previously increased. This permits the plate 87 to lock gradually onto the second drum 79, as it is driven downwardly by the cam track and cam 93, 94 in the manner aforesaid.

It will be observed that this counter works in both directions of rotation, to add or subtract digits, whereas the counters of Figs. 1 to 4 embodiments, work only in the additive direction. Also in the embodiment of Figs. 9 and 10, the higher indicia drums, are firmly locked in position, except during the carry-over period. Also, and contrary to previously known counters, by reducing the dimensions of the structure, none of the parts become too small to be stamped, so that instead of the die cast or heavy metal constructions required in previous counters, the components of this counter can be stamped from exceedingly thin sheet metal, which makes them very light in weight and reduces considerably the requisite torque applied thereto.

Figs. 11 to 13 inclusive show a modification of the invention wherein the counters may be quickly and easily cancelled, i. e., restored to their zero settings. Mounted upon the first eccentric is a finger 105, which is secured to the eccentric, as at 106, this finger having the configuration, in plan, as shown at 107, Fig. 13, which latter represents the corresponding figure for the second drum 108a. Rotatably mounted on the first eccentric 100 is a spur gear 108, provided with nine peripheral teeth as at 109, the depressions between which, such as 110, are engageable by a pawl 111 as explained below. Also the spur gear 108 is provided on its left face, Figs. 11 and 12, with nine equi-spaced upstanding pins, as at 112, adapted successively to seat in corresponding depressions or notches, such as 113, formed in the right hand face, Fig. 11, of a flanged extension 114, of a second eccentric 115 on which a second drum 108a, is angularly shiftable. This eccentric 115 is rotatable on the drive shaft 102. Such internally notched extension and said rigidly mounted pins constitute internal gear with planetary gear means.

The pawl 111, which is arcuate shaped, as shown in Fig. 12, is pivotally mounted, at its approximate center, on a shaft 116, fixed to the frame of the counter in a manner generally similar to shaft 51 of the Figs. 3 and 4 embodiment. This pawl has a hook-like terminus, 117 at its right end, Fig. 12, which is seatable in the depressions 110 of the spur gear 108, and in the manner illustrated in Fig. 12. This terminus 117 of the pawl has mounted thereon a pin 118, which projects from its under side, Fig. 12, and is engageable in the notches, such as 119, of a ratchet face 120, cut or formed in the right

hand peripheral surface, Fig. 11, of the second drum 108a.

The opposite hook-like terminus 121 of pawl 111, is offset as at 122, from the plane of the terminus 117, and is engageable in a single notch 123, formed in the peripheral edge 136 of the flanged extension 114 of the second drum eccentric 115.

Referring to Figs. 11 and 13, the radially extending face 124 of the second drum 108a is arcuately slotted as at 125, and through this slot a pin 126 extends from the hub flange 114, on which this pin is mounted. Secured to this pin is an upstanding lug 127, to which one end of a tension spring 128 is secured, the opposite end of this spring being secured to a pin 129 upstanding from the radial face 124 of the second drum.

Referring more particularly to Fig. 13, it will be observed that the drive shaft 102, is longitudinally notched as at 130, in such manner that upon rotation of the shaft in the clockwise direction, Fig. 12, as to seat 20 in the notch 130, a pawl, such as 131, pivotally mounted on the exposed face of each eccentric 100, 115, etc., as at 132, the free end of pawl 131 being resiliently held against the shaft 102 by means of a spring, such as 133, also mounted on the face of the eccentric, as at 134.

25 In the operation of this counter both the spur gear 108 and the second drum 108a, are prevented from rotating during nine-tenths of each revolution of the first drum 103. This results from the fact that the end 117 of pawl 111 is normally seated in a depression 110 of the spur gear 108, while the pawl pin 118, is normally seated in a notch 119 of the ratchet 120 formed on the second drum 108a. After nine-tenths of a turn of the first drum 103 and eccentric 100, the finger 105 integral with the first drum, trips the pin 118 of pawl 111, thus releasing the second drum 108a, which is thereby rotated one-tenth of a turn, or the amount of one digit, by virtue of the restoring action of the tension spring 128.

To trace through the operation: Assume, referring to Fig. 12, that the finger 105, is disposed on the right hand side of the pin 118, and that this pin is now seated in a notch 119 of the second drum ratchet in the manner shown in Fig. 12. Let a driving force be applied to drum 103 to rotate the shaft counterclockwise, as viewed in Fig. 12. During the ensuing nine-tenths of a complete revolution, the teeth or pins 112 of the spur gear 108 will progressively engage the notches 113 of the eccentric 115 of the second drum, whereby this eccentric will be rotated clockwise, as viewed from the right in Fig. 11, thus to tense the spring 128. During this movement of the second drum eccentric 115, the second drum 108a itself will remain stationary, as will also the spur gear 108, the former due to the seating of the pawl pin 118 in the second drum ratchet face 120, and the latter due to the seating of the pawl lug 117 in a depression 110 of the spur gear 108. Referring to Fig. 13 the effect will be for the pin 126 to move to the left along the arcuate slot 125 and thereby tense the spring 128.

Upon completion of the first nine-tenths of a complete turn of the first drum, the finger 105 thereof will be slightly to the left of the position shown in Fig. 12, and will thereupon engage the pawl pin 118 and knock it out of the second drum ratchet notch in which it is seated. This releases the second drum as a result of which, due to the restoring action of the tension spring 128, the second drum is rotated one-tenth of a turn, and until the pawl pin 118 seats in the next succeeding notch 119 of the second drum ratchet. By this time the finger 105 of the first drum has passed beyond the pawl pin 118, whereby this pin automatically seats in the next succeeding ratchet notch.

For resetting the counters, shaft 116 is manually rotated, until the lug 121 of each pawl 111, engages the helical face 136 of the flanged extension 114 of each eccentric drum hub 115. This frees the spur gears 108 for rotation, and hence also the eccentrics. The reset shaft 102 is now rotated clockwise, Fig. 12, whereby the pawls 131 for the successive drums engage the drive shaft notches 130, following which all drum eccentrics are driven, and with them the drums, until the end 121 of the pawl for each drum, engages the notch 123 of the associated eccentric. When the pawls 111 are again allowed to rotate until the fingers 117 of each seat in a notch 110 of their associated spur gears 108, all counters will be restored to their zero settings.

Figs. 14 and 16, inclusive, show the same counter embodying a resetting mechanism, and also a novel clutch arrangement for driving the counter. Like elements are similarly designated in these figures. The construction and operation of the counter proper is the same as that above described, and hence requires no further comment.

Referring to Figs. 14 to 16, inclusive, the first counter drum 103 is integral with one drum 150 of a clutch 151 having a second clutch drum 152, engageable with and disengageable from the first. The clutch drum 150 is provided, about its periphery, with a plurality of notches as at 153, while the second drum 152, is provided about its periphery with a different plurality of resilient fingers, as at 154, engageable, one at a time in the notches 153, since as explained below, the fingers and notches are relatively so spaced as to have no common factor.

The clutch drums 150 and 152 are concentric with the counter drive shaft 102, drum 150 being journaled thereon as stated, while drum 152 is axially but not rotatively keyed thereto as at 155, which can rotate in an annular space provided in 152. Integral with drum 152 is a pinion gear 156 for driving this drum by means of a driving gear 157 meshing therewith. A helical compression spring 158, surrounding shaft 102 is interposed between the clutch drums 150 and 152, or facilitating disengagement thereof as explained below.

Mounted on the opposite end of the counter shaft 102, is a knob 158a having therein a peripheral notch 159, engageable by a pin 160 of a lever arm 161, the other end of which arm is keyed as at 162 to shaft 116 of the counter. Pin 160 projects beyond the plane of the knob 158a, in the manner shown in Fig. 14, to provide a grip for depressing the lever to the dotted line position 161a of Fig. 16, thus to disengage the lever from the knob, and to rotate shaft 116 and the pawls 111a and 111b.

With the lever 161 thus depressed, the knob 158a may be pushed to the right (Fig. 14) carrying with it the counter shaft 102, thus to disengage the clutch drum 152 from the clutch drum 150. Engagement is again effected by pulling the knob 158a to the left against the compression action of the spring 158 interposed between the clutch drums.

It will be observed that since the lever arm 161 is keyed to the shaft 116, on which are mounted the pawls 111a; 111b, etc., described with reference to Figs. 11 to 13, inc., that this releases the counter drums 103, 103a, 103b, for resetting, in the manner above described with reference to Figs. 11 to 13; this cancellation being effected by rotation of the knob 158a.

When shaft 102 is pushed to the right the pin 163 disengages a notch 164 in the frame 164a. During the rotation of shaft 102 the surface of the frame 164a prevents the shaft 102 from sliding to the left until rotation is completed. In this way the clutch remains disengaged.

Now reverting to the clutch mechanism, it will be noted that in the specific embodiment shown, that the clutch drum 152 is provided with seven equi-spaced fingers 154, while drum 150 is provided with twelve equi-spaced notches 153. Since there are thus seven fingers on drum 152 and twelve notches on drum 150, they have no common factor, so that whatever their relative rotative positions, it is impossible that at least one of the clutch fingers will be further away from a notch than one over 7 x 12' or $\frac{1}{84}$ of a turn. The same is true for other combinations of numbers which have no common factor, so that the error in rotative displacement of clutch member 152 with respect to clutch member 150, before one of the fingers of the former engages a notch of the latter, as at 165, can be made as small as desired. Also it will be observed that when engagement is thus effected the clutch drums are lockingly rather than merely frictionally engaged with one another.

What is claimed is:

1. In a counting device: a first and lower indicia drum; a second and higher indicia drum; an eccentric angularly shiftable with said first drum; internal gear means and meshing planetary gear means operatively associating said eccentric and second indicia drum whereby angular motion of said eccentric in one direction angularly shifts one of said gear means in the opposite direction; detent means for holding said second indicia drum against rotation during a preselected angular shift of said eccentric in such first direction; means for rendering momentarily ineffective said detent means in response to such preselected angular shift of said eccentric, and means

for advancing said second indicia drum when said detent means are so momentarily ineffective.

2. In a counting device: a first and lower indicia drum; a second and higher indicia drum; a shaft for mounting said drums; an eccentric on said shaft angularly shiftable with said first drum; internal gear means and meshing planetary gear means operatively associating said eccentric and second indicia drum whereby angular motion of said eccentric in one direction angularly shifts one of said gear means in the opposite direction; detent means for holding said second indicia drum against rotation during a preselected angular shift of said eccentric in such first direction, detent shifting means, said detent means being momentarily rendered ineffective by such detent shifting means which are angularly shiftable in response to motion of said eccentric; and means for advancing said second indicia drum when said detent means are so momentarily ineffective.

3. In a counting device in combination: a first and lower indicia drum, a second and higher indicia drum, a shaft integral with said first drum, an eccentric integral with said shaft, a spur gear journaled to said eccentric, an internal ring gear integral with said second drum, said spur gear having one less tooth than said ring gear and meshing therewith, a ratchet cutout extending peripherally about the second drum, an angular pawl pivoted at its apex and having a pin secured to one leg engaging said ratchet, said spur gear having a prong normally engaging a second leg of said pawl, a tension spring linking said spur gear to said first pawl leg, whereby rotation of said first drum in one direction rotates said spur gear in the opposite direction until the prong thereon engages said pin on said pawl to disengage the latter from said ratchet, whereupon said tension spring rotates said spur gear and the internal ring gear on such second drum meshed therewith into engagement respectively with the second leg of said pawl and said pin, said second drum having been thereby angularly advanced one ratchet tooth.

4. An intermittently actuating reduction gear mechanism comprising: a driving shaft, an eccentric and a cam integral therewith, a spur gear journaled on said eccentric, a driven member journaled to said shaft and having, integral therewith an internal ring gear meshing with said spur gear, said spur gear having one less tooth than said ring gear, a carry-over member journaled to a shaft paralleling said drive shaft, a disc integral with said spur gear having a pair of spaced cutouts in the peripheral edge thereof, forming a prong therebetween, said carry-over member having a pair of radially extending prongs positionable respectively in said cutouts with said disc prong therebetween, a disc integral with said driven member having Geneva cutouts in its peripheral edge, a Geneva cam on said carry-over, positioned to engage said cutouts, and a cam integral with said driven shaft adapted during rotation thereof to engage for a portion of each cycle of rotation, one prong of said carry-over thereby to rotate the same through a small angle, whereby upon continued rotation of the drive shaft in one direction, said spur gear is oppositely rotated thereby to rotate said carry-over until the Geneva cam thereon is disengaged from a cutout of said Geneva cam, whereupon said cam integral with said drive shaft engages one leg of said carry-over and thereby rotates the same and with it said pronged disc and spur gear until said Geneva cam engages and seats in the succeeding cutout of said Geneva cam.

5. In a counting device in combination: a drive shaft, a first and lower indicia drum integral with said shaft, a second and higher indicia drum adjacent thereto and journaled to said shaft, an eccentric integral with said first drum and adjacent the second, a spur gear rotatable on said eccentric, said spur gear meshing with an internal ring gear integral with said second drum, said spur gear having one less tooth than said ring gear, a carry-over pivoted to a fixed shaft paralleling said drive shaft, said carry-over having a slotted aperture and a pair of spaced prongs, said aperture being disposed in a different plane from that of said prongs, a pin secured to said spur gear engaged in said slotted opening, and a pin secured to said first drum adapted to engage said prongs, a cam member interposed between said drums, and means mounting the same for oscillating, rectilinear displacement, said cam member having a central aperture through which the pin secured to said spur gear extends, a pin

secured to said spur gear and a cam slot formed in said first drum engaging said pin, said cam and carry-over member so cooperating as to prevent rotation of said second drum only for a preselected interval of a complete cycle of rotation of said first drum.

6. In a counting device the combination: a first eccentric having a first drum secured thereto, a trip finger secured to such eccentric for angular motion therewith, a spur gear journaled upon such first eccentric, such spur gear having a plurality of peripheral teeth, a second eccentric angularly shiftable about a common axis with said first eccentric and having an internal ring gear formed in one face of a flanged extension thereof, a second drum journaled upon said second eccentric and angularly shiftable thereupon, said spur gear having a plurality of pins secured thereto one less in number than the number of teeth in said internal ring gear, the number of teeth of said spur gear being equal to the number of such pins, said second drum having a ratchet surface extending peripherally thereabout, a pawl member pivoted intermediate the extremities thereof and having a pin secured to one leg for engaging said ratchet and also having a hook-like terminus at one extremity settable between the teeth of such spur gear whereby such second drum can be held against angular motion in one direction and said spur gear can be held against angular motion in either direction, the opposite extremity of such pawl having a secondary hook-like terminus offset from the plane of the first-mentioned terminus, the aforementioned flanged extension of the second eccentric having a single notch in the periphery thereof for engaging said secondary offset hook-like terminus, means for resiliently holding said second drum in a preselected angular relation with such second eccentric upon which it is journaled whereby such drum is angularly shiftable but is urged toward such preselected angular relation, a drive shaft for supporting said eccentrics, rotation of said first drum in one direction being effective angularly to shift said second eccentric in an opposite direction thereby to tense the aforementioned resilient means, said second drum remaining stationary until said trip finger engages said pin on said pawl thereby to disengage same from said peripheral ratchet on the second drum whereupon said resilient means angularly advances said drum one ratchet tooth, and pawl means associated with each of said eccentrics and such shaft whereby such eccentrics are rotatable together by rotation of such shaft in one direction of angular motion, whereby said drums can be shifted to a preselected norm in response to such shaft rotation when said secondary offset hook-like terminus is in engagement with the periphery of said flanged extensions.

7. In a counting device the combination: a first eccentric, a first drum mounted for rotation with said eccentric, a spur gear journaled upon such first eccentric, such spur gear having a plurality of peripheral teeth, a second eccentric angularly shiftable about a common axis with said first eccentric and having an internal ring gear formed in one face of a flanged extension thereof, a second drum journaled upon said second eccentric and angularly shiftable thereupon, said spur gear having a plurality of pins secured thereto, at least one less in number than the number of teeth in said internal ring gear, said second drum having a ratchet surface extending peripherally thereabout, a pawl member pivoted intermediate the extremities thereof and having a pin secured to one leg engaging said ratchet and also having a hook-like terminus at one extremity for engaging such spur gear whereby such second drum and such spur gear can be concurrently held against angular motion, means for resiliently holding said second drum in a preselected angular relation with such second eccentric upon which it is journaled whereby such drum is angularly shiftable but is urged toward such preselected angular relation, rotation of said first drum in one direction being effective angularly to shift said second eccentric in an opposite direction thereby to tense the aforementioned resilient means, and ratchet pin trip means angularly shiftable with said first drum, said second drum remaining stationary until said trip means engages said pin on said pawl thereby to disengage same from said peripheral ratchet on the second drum whereupon said resilient means angularly advances said drum one ratchet tooth.

8. In a counting device, the combination: a first and lower indicia drum, a second and higher indicia drum, a pair of eccentrics one for mounting each of such drums,

shaft means for coaxially mounting said eccentrics, said first drum being secured to said first eccentric for angular motion therewith, a spur gear journaled upon said first eccentric for angular motion relative thereto, a pivotally mounted pawl, said spur gear having a plurality of pins secured to one face thereof, said pins being equal in number to the number of teeth of such spur gear, said second eccentric having a face in which is formed an internal ring gear having a number of teeth, at least one greater than the number of said pins, said pins being secured equidistant about the center of said spur gear and positioned for engaging the teeth of said internal ring gear, said second eccentric being angularly shiftable relative to said shaft means, said second drum having a peripheral ratchet formed thereabout, said pawl having a projection upon one of the legs thereof for engaging such peripheral ratchet concurrently with the engagement thereof with said spur gear thereby to hold said drum and spur gear against angular motion, a trip finger secured to said first eccentric for angular motion therewith and positioned for disengaging said projection from such ratchet thereby to free such second drum for angular motion but concurrently holding said spur gear against angular movement, a tension spring linking said second drum and said second eccentric, whereby rotation of said first drum in one direction with said peripheral ratchet and spur gear engaged by said projection and pawl, rotates said second eccentric in an opposite direction until such trip finger engages said projection to disengage the latter from said peripheral ratchet whereupon said tension spring by its restorative action advances said second drum and the ratchet thereof into engagement with another ratchet tooth.

9. In a counting device, the combination: a first and lower indicia drum, a second and higher indicia drum, a pair of eccentrics one for mounting each of such drums, a shaft means for coaxially mounting said eccentrics, said first drum being secured to said first eccentric for angular motion therewith, a spur gear journaled upon said first eccentric for angular motion relative thereto, an angularly shiftable pawl pivotally mounted intermediate its extremities and having planar offset termini, said spur gear having a plurality of pins secured to one face thereof, said pins being equal in number to the number of teeth of such spur gear, said second eccentric having a face in which is formed an internal ring gear having a number of teeth, at least one greater than the number of said pins, said pins being secured equidistant about the center of said spur gear and positioned for engaging the teeth of said internal ring gear, said second eccentric being angularly shiftable relative to said shaft means, said second drum having a peripheral ratchet formed thereabout, said pawl having a projection upon one of the legs thereof for engaging such peripheral ratchet concurrently with the engagement by one of the termini thereof with said spur gear thereby to hold said drum and spur gear against angular motion, a trip finger secured to said first eccentric for angular motion therewith and positioned for disengaging said projection from said ratchet thereby to free such second drum for angular motion but concurrently holding said spur gear against angular movement, a tension spring linking said second drum and said second eccentric, whereby rotation of said first drum in one direction with said peripheral ratchet and said spur gear engaged by said projection and termini, rotates said second eccentric in an opposite direction until such trip finger engages said projection to disengage the latter from said peripheral ratchet whereupon said tension spring angularly shifts said second drum and the ratchet thereof into engagement with another ratchet tooth, said face of said second eccentric having a peripheral projection for engaging the other of said termini in response to angular shifting of said pawl to place such termini in engagement with said periphery of said eccentric, and pawl means associated with each eccentric and with such shaft whereby said eccentrics can be rotated in a common direction opposite to that first mentioned for the actuation of the counting device.

10. In a counting device: a pair of coaxially mounted eccentrics; a first indicia drum mounted for angular movement coaxially with the first of said eccentrics; a second indicia drum mounted for angular movement coaxially relative to the second of such eccentrics, the latter having an internal ring gear secured thereto for rotation therewith; a spur gear rotatably journaled upon said first eccentric and having equi-spaced projection means there-

on for engaging said internal ring gear, there being at least one less projection of said projection means than teeth of said internal ring gear; a ratchet secured to said second drum; pivotally mounted pawl means for engaging said spur gear and holding same against rotation during rotation of said first eccentric, said pawl means having a ratchet pin angularly shiftable therewith in pivotal motion and for engaging said ratchet; a tension spring linking said second eccentric and its indicia drum, whereby rotation of said first eccentric in one direction angularly shifts said second eccentric in an opposite direction thereby to tension said spring; and means rotatable with said first eccentric for disengaging said ratchet pin from said ratchet means thereby allowing said second drum to advance at least one ratchet tooth under the restoring action of said tension spring.

11. In a counting device, a pair of adjacent eccentrics having axes of rotation substantially perpendicular to a common plane; a first indicia means mounted for angular movement with a first of said eccentrics; a second indicia means mounted for angular motion relative to the second of said eccentrics; internal gear means and meshing planetary gear means operatively associating said first and second eccentrics, said gear means each having a different number of teeth, one of such gear means being journaled upon said first eccentric and the other of said means being secured to the second eccentric for rotation therewith; ratchet means coaxial with said second indicia means and secured thereto; pivotally mounted pawl means for holding that one of the aforementioned gear means against rotation which is journaled upon said first eccentric, ratchet pin means mounted for angularly shifting with such pawl means and for engaging said ratchet means; spring means for linking said second eccentric and said second indicia means, whereby rotation of said first eccentric in one direction angularly shifts said second eccentric in an opposite direction thereby to tension said spring; means rotatable with said first eccentric for momentarily disengaging said ratchet pin and ratchet means thereby causing said second indicia means to advance under the influence of said spring means and to be arrested by said pin and ratchet means.

12. In a counting device; a pair of adjacent eccentrics having axes of rotation substantially perpendicular to a common plane; a first indicia means mounted for angular movement with and coaxially of a first of said eccentrics; a second indicia means mounted coaxially of the second of said eccentrics and for angular motion relative thereto; an internal gear and meshing planetary gear operatively associating said first and second eccentrics, said gears having different numbers of teeth, one of such gears being journaled upon said first eccentric and the other of said gears being secured to the second eccentric for rotation therewith; ratchet means coaxial with said second indicia means and secured thereto; pivotally mounted pawl means for holding that gear against rotation which is journaled upon said first eccentric, ratchet pin means mounted for angularly shifting with such pawl means and for engaging said ratchet means; spring means for linking said second eccentric and said second indicia means, whereby rotation of said first eccentric in one direction angularly shifts said second eccentric in an oppo-

site direction thereby to tension said spring; means rotatable with said first eccentric for momentarily disengaging said ratchet pin and ratchet means after a preselected angular shift of such first eccentric thereby causing said second indicia means to advance under the restoring action of said spring means and to be arrested by said pin and ratchet means; indicia reference means associated with said second eccentric and angularly shiftable therewith, and means operable in response to disengagement of said pawl means from such aforementioned gear means for movement into the path of such indicia reference means whereby all of said indicia means can be angularly shifted each to a preselected angular norm in response to rotation of said eccentrics in a common direction.

13. In a counting device: a pair of adjacent eccentrics having axes of rotation substantially perpendicular to a common plane; a first indicia means mounted for angular movement with and coaxially of a first of said eccentrics; a second indicia means mounted coaxially of the second of said eccentrics and for angular motion relative thereto; internal gear means and meshing planetary gear means operatively associating said first and second eccentrics, one of such gear means being journaled upon said first eccentric and the other of said gear means being secured to the second eccentric for rotation therewith; ratchet means coaxial with said second indicia means and secured thereto; pivotally mounted pawl means for holding that of the aforementioned gear means against rotation which is journaled upon said first eccentric, ratchet pin means mounted for angularly shifting with such pawl means and for engaging said ratchet means; spring means for linking said second eccentric and said second indicia means, whereby rotation of said first eccentric in one direction angularly shifts said second eccentric in an opposite direction thereby to tension said spring; means rotatable with said first eccentric for momentarily disengaging said ratchet pin and ratchet means thereby causing said second indicia means to advance under the influence of said spring means and to be arrested by said pin and ratchet means; indicia reference means associated with said second eccentric and angularly shiftable therewith, means operable in response to disengagement of said pawl means from such aforementioned gear means for movement into the path of such indicia reference means whereby all of said indicia means can be angularly shifted each to a preselected angular norm in response to rotation of said eccentrics in a common direction, a counter shaft for mounting said eccentrics and shiftable axially relative thereto; clutch means having a driving member for engaging a driven member secured to said first eccentric, one of said members being axially shiftable with said counter shaft to disengage said clutch means; detent means for holding said counter shaft in a preselected angular position; means for driving said eccentrics by said counter shaft in response to rotation of the latter in said common direction, and means for shifting said pawl means out of engagement with said gear means and into the path of said indicia reference means in response to disengagement of said detent means.
